UNITED STATES PATENT OFFICE.

JOHN B. MILLER, OF CHICAGO, ILLINOIS.

INHALER.

1,072,759.

Specification of Letters Patent. Patented Sept. 9, 1913.

Application filed February 27, 1913. Serial No. 750,970.

To all whom it may concern:

Be it known that I, JOHN B. MILLER, a citizen of the United States, and a resident of Chicago, county of Cook, and State of Illinois, have invented certain new and useful Improvements in Inhalers, of which the following is declared to be a full, clear, and exact description.

This invention relates to inhalers, and its primary object is to provide an inhaler of simple construction which nevertheless is very effective in its action.

Another object is to provide an inhaler capable of supplying a comparatively large volume of medicinal vapors to the patient whereby speedy and effective relief may be obtained from the use of the inhaler.

Another object is to provide an inhaler which may be held over the nose and mouth of the patient, and so arranged that the exhalations do not contaminate the contents of the inhaler to any appreciable extent.

Another object is to provide containers or receptacles in an inhaler that may be readily closed (when not in use), to prevent unnecessary escape of the volatile substances contained therein.

Another object is to provide an inhaler that may be readily filled and emptied.

With all these and other objects and advantages in view, this invention consists in the several novel features hereinafter fully set forth and claimed.

This invention is clearly illustrated in the drawing furnished herewith, in which—

Figure 1, is a perspective view of an inhaler embodying the preferred form of the present invention and showing the same applied to a patient; Fig. 2, is a perspective view of the inhaler, looking at the side opposite to that seen in Fig. 1, and showing one of the receptacles partly withdrawn from its pocket; Fig. 3, is a detail, cross section through the inhaler, and Fig. 4, is a perspective view of one of the receptacles with its open work cover partially removed.

In said drawing, 10, designates a receptacle holder, here shown as comprising two similar, open ended, box like pockets, 11, 11, connected at their rear edges by a curved back piece, 12, preferably constructed of some flexible material, whereby the two pockets may be spread farther apart or brought closer together to adjust the inhaler to the nose of a patient, it being desirable

that the medicament receiving receptacles 13, 13, which are carried in the pockets, be held close to the sides of the patient's nose. The back piece 12, may be secured to the pockets, 11, 11, in any suitable manner, as for instance, by soldering or riveting it thereto as the case may be. As shown, each of said pockets has a solid outer side wall, 14, and a marginal inner side wall 16, connected by walls 15, thus forming a rectangular pocket 65 for receiving the receptacles and having a large opening 17, at one side thereof. It is apparent that the back piece 12, and pockets 11, 11, with the receptacles 13, therein, form a channel like structure having a longitudinal, open ended, space which is adapted to receive the patient's nose, the best results being obtained by holding the upper end of the inhaler over the nostrils, and the lower portion covering the mouth of the patient. 70 In this manner the incoming air passes along the open sides of the receptacles, containing the volatile medicinal substances, and absorbs large quantities of the vapors flowing therefrom, which pass to and are inhaled by the patient.

In the present construction of the receptacles 13, they are shown as of box like formation, each having a solid back 18, sides 18^a, and end pieces 18^b. The receptacles 85 are of substantially the same cross section and size as the interiors of the pockets and slide freely therein; they may be held therein solely by friction against the walls of the pockets. Associated with each receptacle is 90 an open work cover 20, that fits in the open side, 19, of the receptacle, and, as shown, each of said covers may comprise a rectangular frame 21, to which is secured a piece of gauze or fine wire mesh screen 22. Each receptacle is employed to contain a medicinal substance, or a filler of some kind, for instance, absorbent material such as cotton, felt, or the like 23, which may be saturated with the medicinal substances, and the open 100 work cover 20, acts to hold the filler in place while permitting the free volatilization of the medicinal substances. The open work cover, having been placed upon the filler in the receptacle, the latter may be inserted 105 into one of the pockets with the open side of the receptacle exposed to and facing the open space between the two pockets.

If desired, suitable means may be employed for holding the inhaler in place upon 110

the patient's face, and said means are here shown as comprising an elastic band 24, which extends through holes 25, in the back piece 12; said band may be looped around 5 the ears of the patient after the inhaler has been adjusted over the nose and mouth, thus securely holding it in place.

In use the receptacles are supplied with suitable volatile medicinal substances, the 10 open work covers put in place, and the receptacles inserted in the pockets with their open sides facing each other. The inhaler is then held in place on the patient's face as shown in Fig. 1, thus practically closing the 15 open side thereof. As heretofore stated, during inhalation, air entering the space between the receptacles, from below, and passing the open sides thereof, absorbs large 20 quantities of the volatile medicinal substances, which are inhaled by the patient. The exhalations pass down between the receptacles and while they absorb and carry away some of the vapors, they do not contaminate the medicinal substances to any 25 appreciable extent. Furthermore in a device constructed as hereinabove set forth, there is no danger that moisture will be deposited upon the exposed portions of the receptacles as might be the case where the 30 receptacles are held in a horizontal plane underneath the nose and mouth.

When not in use, the receptacles may be withdrawn from the pockets and by reversing them so as to bring the solid backs 35 thereof to the open sides of the pockets, their contents are wholly inclosed by the walls of the pockets and receptacles, respectively, thereby preventing the escape of any appreciable amount of the volatile substances. There being two receptacles, one 40 sort of medicinal ingredient may be put in one receptacle, and a different kind may be put in the other receptacle, in case it should be impractical to intermix the two kinds of 45 ingredients.

More or less variation of the exact details of construction are possible without departing from the spirit of this invention, and I do not, therefore, desire to limit myself 50 to their exact form except as may be necessitated by the prior state of the art.

I claim as new and desire to secure by Letters Patent—

1. An inhaler of the class described, comprising a receptacle holder, and a pair of spaced, medicament receiving receptacles carried by said holder and having a nose receiving space therebetween, each receptacle having an open side facing the other open 60 side, for exposing its contents.

2. An inhaler of the class described, comprising a receptacle holder, and a pair of medicament receiving receptacles, removably secured to said holder, and extending 65 in approximately parallel relation to each

other, said receptacles being spaced apart to leave a nose receiving space therebetween, each receptacle having an open side facing the open side of its companion receptacle.

3. An inhaler of the class described, comprising a receptacle holder, consisting of a flexible back piece and a pair of receptacle supports secured thereto, and a pair of medicament receiving receptacles carried by said supports in approximately parallel relation 75 to each other, each receptacle having an open side, facing the open side of the companion receptacle, for exposing its contents.

4. An inhaler of the class described, comprising a receptacle holder having a pair of 80 companion pockets, formed with openings facing each other, and a pair of medicament receiving receptacles removably secured in said pockets and having open sides registering with the openings in the pockets, each 85 pocket and the receptacle therein being spaced from the other pocket and its receptacle to leave a nose receiving space therebetween.

5. An inhaler of the class described, comprising a receptacle holder having a pair of 90 companion pockets formed with open sides that face each other, and a pair of medicament receiving receptacles slidably and removably secured in said pockets and having 95 open sides registering with the openings in the pockets.

6. An inhaler of the class described, comprising a receptacle holder of channel like 100 formation, and a pair of medicament receiving receptacles secured at the sides of said holder, each receptacle having an open side facing the open side of the other receptacle, the two open sides of said receptacles being spaced apart to leave a nose receiving 105 space therebetween.

7. An inhaler of the class described, comprising a back piece, and a pair of pockets secured to said back piece and extending away therefrom in the same general direction, said pockets having open ends, and each pocket having an open side facing the open side of the opposite pocket, and a pair of medicament receiving receptacles, one 110 slidably and removably secured in each 115 pocket, each receptacle having an open side capable of registering with the side opening in its pocket.

8. An inhaler of the class described, comprising a pair of pockets having open sides 120 facing each other, and a pair of medicament receiving receptacles having open sides and adapted to be secured in said pockets with the open sides registering with the side openings in the pockets, and open work covers, 125 one for each receptacle.

9. An inhaler of the class described, comprising a holder, a pair of medicament receiving receptacles carried by said holder, and having open sides facing each other, and 130

open work covers across the open sides of said receptacles.

10. An inhaler of the class described, comprising a receptacle holder, a pair of medicament receiving receptacles removably secured upon said holder and extending approximately parallel with each other, each receptacle having an open side facing the open side of the other receptacle, and an open work cover extending across the open side of each receptacle.

11. An inhaler of the class described, comprising a receptacle holder, a pair of box like medicament receiving receptacles secured to said holder and extending approximately parallel with each other, each receptacle having an open side facing the open

side of the opposite receptacle, and a wire mesh cover for each receptacle extending across the open side thereof.

20

12. An inhaler of the class described, comprising a channel like structure having a longitudinal nose receiving space, open at the front and top and bottom, a pair of medicament receiving receptacles forming a part of said structure, each receptacle having an open side facing the open side of the other receptacle, and means for securing said structure on the face of the patient.
